(57) **CLAIM**

The ornamental design for a hood for a vehicle, as shown and described.

DESCRIPTION

This application contains subject matter related to the following co-pending U.S. design patent applications:

Application Ser. No. 29/800,398, filed herewith and entitled “Hood for a Vehicle”;

Application Ser. No. 29/763,263, filed Dec. 22, 2020 and entitled “Hood for a Vehicle;”

Application Ser. No. 29/763,257, filed Dec. 22, 2020 and entitled “Truck Cab, Toy and/or Replicas Thereof;” and Application Ser. No. 29/763,258, filed Dec. 22, 2020 and entitled “Truck Cab, Toy, and/or Replicas Thereof.”

FIG. 1 is a left, front perspective view of a hood for a vehicle according to the design;

FIG. 2 is a right, rear perspective view thereof;

FIG. 3 is a front view thereof;

FIG. 4 is a left side view thereof;

FIG. 5 is a right side view thereof; and,

FIG. 6 is a top view thereof.

The broken lines in the drawings illustrate environmental subject matter only and form no part of the claimed design.

1 Claim, 6 Drawing Sheets
